ARTHUR R. BLOOM.
BY HIS ATTORNEY.

James F. Williamson

UNITED STATES PATENT OFFICE.

ARTHUR R. BLOOM, OF MINNEAPOLIS, MINNESOTA.

SLOGAN CARD GAME.

Application filed October 25, 1924. Serial No. 745,795.

To all whom it may concern:

Be it known that I, ARTHUR R. BLOOM, a citizen of the United States, residing at Minneapolis, in the county of Hennepin and State of Minnesota, have invented certain new and useful Improvements in a Slogan Card Game; and I do hereby declare the following to be a full, clear, and exact description of the invention, such as will enable others skilled in the art to which it appertains to make and use the same.

This invention relates to a game, particularly to the game apparatus used in playing a card game. The cards employed are similar in size to the ordinary playing card. As is well known, there are used in modern advertising a great many catch phrases or slogans. The present game is designed to have utility in advertising in connection with these slogans as well as having great utility and affording a game of much science and pleasure when used with other inscriptions than advertising slogans.

It is an object of this invention to provide a game using an apparatus including a key-member having printed thereon a plurality of groups of characters and also comprising a series of members, each of which bears one of the characters appearing in said plurality of groups.

It is a further object of this invention to provide a card game comprising a pack of cards including a key-card having thereon an inscription, such as an advertising slogan and a series of cards, each of which carries a letter of other character appearing in said slogan.

It is also an object of the invention to provide such a pack of cards, together with means for holding a key-card in erect and visible position, and it is a further object of the invention to have different portions of the slogan or inscription on the key-card distinguished by some characteristic, such as the different parts being in different colors and then to have the cards bearing the words appearing in such parts to have the same characteristics or colors.

These and other objects and advantages of the invention will be fully set forth in the following description made in connection with the accompanying drawings in which like reference characters refer to the same parts throughout the different views, and in which,

Fig. 1 is a face view of a key-card used

showing the same in a holder for maintaining the card erect;

Fig. 2 is a face view of one of the parts of a series bearing one of the letters of the inscription on the key-card;

Fig. 3 is a face view of another card of the series of cards showing a different letter;

Fig. 4 is a view similar to Figs. 2 and 3 showing a punctuation mark used in the series;

Fig. 5 is a face view of a part of a card having the inscription shown on the card in Fig. 1 but having different lines of the inscription of different colors;

Figs. 6 and 7 show face views of cards of the series to be used with the key-card shown in Fig. 5, the letters on the cards in Figs. 6 and 7 being colored to suit the colors of the same letters on the key-card; and

Fig. 8 is a view in side elevation of the holder for the key-card showing an edge view of said card.

Referring to the drawings, in Fig. 1 is shown a key-card and there will be one key-card in each pack of cards used. While this key-card may have any desired inscription thereon or any desired groups of characters, in the embodiment of the invention illustrated the key-card is shown as bearing a well known advertising slogan or inscription, namely, "Even-tually, Gold Medal Flour, Why Not Now? Wash-burn-Crosbys."

The key-card is shown having the word "Slogan" at the top thereof, which term is used to designate applicant's game. In addition to the key-card in the pack there will be a series of cards, each of which bears a letter of character appearing on the key-card including the punctuation marks used in the inscription or groups of characters. There will thus be as many cards in the pack as there are characters in the inscription on the key-card, including the punctuation marks, plus one card which will be the key-card. In the drawings two cards are illustrated showing two of the letters of the inscription. Fig. 2 shows the card having the letter "E," and in the pack there will be three such cards bearing the letter "E" as the said letter appears three times in the inscription. It will be seen that Fig. 2 shows one of the vowel letters; and Fig. 3 shows one of the cards of the pack having one of the consonant letters, namely, the letter "N."

There will be four such cards having the letter "N" as said letter appears four times

in the inscription. Fig. 4 shows a card having one of the punctuation marks used in the inscription, namely the interrogation point used after the word "Now." There will be one such card in the pack and there will also be cards having thereon a period and a hyphen. It will also be understood that there will be other cards in the pack similar to the cards shown in Figs. 2 and 3, excepting that they will carry other letters of the inscription and there will be as many cards of each letter as the times said letter appears in the inscription. In the pack of cards, therefore, used with the key-card shown in Fig. 1, there will be fifty-two cards.

In playing the game, the key-card is disposed and held in erect position so as to be visible to the players and for this purpose a holding means for the card is provided. While any suitable holding means may be used, in the embodiment of the invention illustrated, said means is shown as a simple clip 9 formed from a flat strip of metal such as sheet metal having rounded ends and having one end portion bent at a right angle to the remaining portion of the clip. A narrow strip or tongue 10 is cut centrally from the right angle end portion of the clip and is pressed outwardly into the shape shown in Fig. 8. The clip will be made of resilient or spring metal and the card designated 11 can thus be placed between the tongue 10 and the remaining end portion of the clip and held therein in erect position.

In Fig. 5, a modified form of key-card is shown which bears the same inscription as the card shown in Fig. 1. In Fig. 5, however, the different lines of the inscription are indicated as being printed in different colors. The top line comprising the word "Even-tually" and the third line from the top comprising the words "Why Not Now" are indicated as being red in color, while the second line comprising the words "Gold Medal Flour," and the bottom line comprising the words "Washburn-Crosbys" are shown as printed in blue. In the pack of cards including the key-card shown in Fig. 5 there will be a series of cards, each representing one of the characters in the inscription on the key-card, as already described in connection with Figs. 1 to 4. The cards in the series of cards, however, will have the letters thereon in different colors and these colors will correspond to the color of the line in which the letter appears on the key-card. Thus, in Fig. 6, a card is shown bearing a letter "O" and this "O" will be in blue, as indicated in said figure, to correspond to the "O" in line 2 of the key-card shown in Fig. 5.

In Fig. 7 a card is shown bearing the letter "T" and this "T" will be in red, as indicated to correspond to the color in line 3 from the top of the key-card in which "T"

will appear in the word "Not." Certain of the characters in the groups are thus designated additionally to the character designation and certain of the characters on the cards are also designated additionally to 70 their character designations, the additional designations on the key card and the other cards corresponding.

With the pack of cards such as shown and described, many interesting games may 75 be played, which games will require considerable skill or science. While a great number of games may be played only a few thereof will be indicated.

In playing the game, the key-card will be 80 taken from the deck and placed in the holder in erect position on the playing board or table so as to be visible to all of the players. The cards will now be shuffled and dealt by the dealer successively to the players, each 85 player receiving a certain number of cards, for instance, five. The dealer is determined in the usual manner by cutting the cards. The dealer drawing the letter nearest the 90 beginning of the inscription or nearest the front of the alphabet gets the deal. Obviously, other rules for determining the deal could be used. Each player being dealt his hand, the remaining cards are placed on the table face downward. The player next to 95 the dealer now plays a card face upward on the table and opens a trick. Each trick will comprise the cards shown in one word of the inscription on the key-card or an hyphenated division of such word. In order 100 not to have the tricks too long, long words will be divided by hyphens. In Fig. 1, the words, "Even-tually" and "Wash-burn" are shown so divided. The players will now 105 play their cards in sequence, each playing on a trick already started or opened or starting a new trick of some other word. The trick is closed when all of the letters therein have been played and the last person playing a vowel on the trick takes the trick. As 110 each player plays a card from his hand, he draws another card from the pack to replace this card. The game thus continues until all of the tricks have been opened or taken and all of the cards played. When a vowel 115 is played as an opener in a single vowelled word the trick is killed and such play is known as a "kill." A kill of a trick containing one or more vowels can be accomplished after the trick has been opened by 120 making the vowel play or the last vowel play thereon before all of the consonants in the trick have been played. A letter, such as I and A cannot be killed as tricks. After the trick has been killed the last consonant letter played on such trick is known as a 125 "burial." When such burial play is made the trick is not taken by the party playing the last card but is stacked face down and kept until the end of the game. Transfers 130

of cards from one trick to another, either from a live or killed trick, may be made when by so making a transfer, the trick can be placed in condition to be taken by a card from the hand of one of the players. A trick, however, cannot be opened by a transfer. The game is usually ended after each player has had a deal. If desired, a plurality of deals may be allowed for 10 each player. The game can be played by two or more persons, either as individuals or as partners. After the game is over the points are determined as follows:

	Points.
15 Each vowel for the player possessing the same -----	2
Each honor consonant, (this will include the consonants S. L. G. N.)-----	1
Each "burial" play-----	5
20 And the highest number of tricks taken by any one player or group of partners-----	10

Another game is known as Slogan-Sweeps. In this game, the cards are shuffled and 25 dealt, as above described, but in this game the vowels have no value over the consonants in taking tricks, and the last person playing a card on a trick and closing the word can take the trick and the letters of the 30 word must be consecutively played. A word trick, however, may be opened with any letters therein and the letters then played consecutively at both sides of said letter or at both ends of the trick. The players will 35 play in sequence and draw cards, as above described. When a player holds a playable card he is forced to play. If a player should be unable to play, that is to open a trick, or play on an open trick, he will play one 40 card to the table, face up, directly in front of him. Any such table card may be used by any player on an open trick and "transfers" in sequence may also be made of cards from the right or left of any open trick, 45 but such plays must be made before the players plays from his hand, which must be a card that will close and take the trick to which the table plays and transfers were made. In determining the score of the 50 Slogan-Sweeps game, the points are numbered as follows:

	Points.
Each vowel-----	1
Each honor consonant (S. L. G. N.)-----	1
55 Highest number of tricks-----	5

Another game possible with the cards is that of Slogan-Layout. The principle of this game is to reproduce and assemble, as an entirety, the slogan or inscription shown on the key-card, or member. Six cards are dealt to each player and the remainder of the deck used as stock from which to draw. In starting or declaring a line of the inscription the player must play either the 60 first or last letter or punctuation mark of

such line and the lines can be completed or built up only from one end, the players playing in sequence. When any player is unable to open a line or play a card in sequence on an open line, or if he wishes to 70 pass a play he will place one card on the table face up directly in front of him. After each play the players draw one card from the top of the stock or remainder of the deck. Any card or number of cards 75 played to the table may be used by any player or to play to the lay-out of the inscription and transfers may be made from one line to another line but any table play or transfers must be made before the player 80 making the same plays a card from his hand. Any table card may be exchanged by the player for a card in his hand when it is his turn to play and the card taken from the table, that is from the group of cards which he has played to the table in front of him, may be held in his hand for a future play. If a player places any card in the wrong position or makes a transfer in a wrong position and an opponent player 85 discovers the error the latter will declare a "slogun". Also when a vowel is played from his hand the player will declare a "slogun" as he plays the card. If he fails to make the declaration the card remains 90 played as usual but he loses a slogan point. The scoring in the Slogan-Layout game 95 would be as follows:

	Points.
Every "slogun" play-----	1
Building entire word in one play or if 100 partners, in same round-----	2
Closing play of a line-----	3
Last play to layout-----	5

Various games of solitaire may be played 105 with the cards, the object being to get all the cards out of the pack in sequence to reproduce the inscription or slogan by building up the lines, words or other parts thereof or the whole inscription. In playing this, the pack will be shuffled and the player will cut or deal off three cards, or some other number of cards, at a time using only the bottom card of the group of cards dealt off. 110

From the above description it is seen that 115 applicant has provided a game apparatus by means of which many games can be played which will afford much fun and entertainment and require considerable science and skill. The apparatus is particularly adapted for advertising purposes for various advertising slogans, phrases, etc., or may be used to advertise any article or event such as a song, or a campaign of some kind. The game can also be provided with a key-card or member referring to well known subjects, such as fairy tales, titles, etc., and thus be made of general use without any reference to any advertising slogan. The 120 apparatus can be cheaply produced and 125 130

made in various grades to suit the taste of the purchaser.

It will, of course, be understood, that various changes may be made in the form, details, and inscriptions used without departing from the scope of applicant's invention, which, generally stated, consists in a device capable of carrying out the objects above set forth, in the novel parts and combination of parts disclosed and defined in the appended claims.

What is claimed is:

1. A card game apparatus comprising a key-card having thereon an inscription comprising a plurality of characters arranged in a plurality of lines, each line having a distinguishing characteristic, and a series of cards each having thereon one of the letters appearing in said inscription, the letters on the series of cards having the same characteristics as the letters in the respective lines of the inscription.
2. A card game apparatus comprising a key-card having thereon an inscription comprising a plurality of lines, different lines appearing in different colors, and a series of

cards, each carrying thereon a letter appearing in said inscription, and the letters on the cards having the same color as the lines on the key-card in which said letters appear. 30

3. A game apparatus comprising a key-member having thereon an inscription consisting of a plurality of groups of characters, certain of said groups having a distinguishing characteristic, and a series of 35 members each having thereon one of the characters appearing in said plurality of groups, said characters on said series of members having the same characteristic as the group in which they appear. 40

4. A game apparatus comprising a key member having thereon an inscription consisting of a plurality of groups of characters, certain of said characters in said groups being additionally designated and a series of 45 members each having thereon one of the characters appearing in said plurality of groups and certain of said members also being additionally designated in the same manner as said certain characters in said groups. 50

In testimony whereof I affix my signature.
ARTHUR R. BLOOM.
